Gifford & Brown*

UNITED STATES PATENT OFFICE.

THEODORE A. WEBER, OF NEW YORK, N. Y.

SHUTTLE-MOTION FOR LOOMS.

SPECIFICATION forming part of Letters Patent No. 339,239, dated April 6, 1886.

Application filed October 22, 1884. Serial No. 146,231. (No model.)

To all whom it may concern:

Be it known that I, THEODORE A. WEBER, of New York, in the county of New York and the State of New York, have invented a certain new and useful Improvement in Shuttle-Motions for Looms, of which the following is a specification.

I will describe a loom embodying my improvement, and then point out the improvement in claims.

In the accompanying drawings, Figure 1 is a plan view of parts of a loom embodying my improvement, and Fig. 2 is a front elevation of the same.

I have deemed it necessary to illustrate only such parts of a loom as embody my improvement. Other necessary parts of the loom may be of any approved type.

A designates two side pieces, comprised in the frame of the loom.

B designates a shaft, which transmits motion to the parts which embody my improvement, and which I am about to describe. This shaft is journaled in the side pieces, A, and driven in any suitable manner. Near the side pieces, A, the shaft B has affixed to it bevel gear-wheels $a a'$. These bevel gear-wheels mesh with other bevel gear-wheels, $b b'$, which are rigidly secured to vertical shafts C C'. As here shown, these shafts C C' are supported in bearings in inwardly-projecting brackets $c c'$, attached to the side pieces, A. At the upper ends the shafts C C' have disks $c^2 c^3$ affixed to them. These disks have upon their under sides hubs $c^4 c^5$, which rest upon the inwardly-projecting brackets $c c'$ of the side pieces, A, and support the shafts vertically.

D D' designate levers, fulcrumed at the rear ends to pins or studs $p p'$, supported by projections from the side pieces, A. These levers are swung to and fro to impart motion to the shuttles.

Motion is transmitted to the lever D by means of a crank-pin, E, projecting from the disk c^2 of the shaft C, a link-connection being employed between the wrist-pin and the lever. As here shown, the crank-pin has loosely fitted upon it a bar, d, and links $d' d^2$ are pivotally connected to the latter and to the lever D. By these means I am enabled to produce "dwells" of the lever at the ends of its movements, because the crank-pin E at certain por-

tions of its stroke will not impart any appreciable swing to the levers D D' on their fulcrums. The front end of the lever D is pivotally connected to one end of a link, d^3 , which at the other end is pivotally connected to a carriage, F. The carriage F is reciprocated along ways or guides G by the to-and-fro movements of the lever D. As shown, the side edges of the carriage work in grooves in the ways or guides. The ways or guides are secured to the side pieces, A.

H H' are levers, which are fulcrumed between the ends upon studs $f f'$, projecting from the carriage F near its forward end, or, in other words, near the end which is the nearer to the middle of the loom. The forward ends of the levers H H' are adapted to grip the shuttles which are employed in the loom. To adapt the loom for using two shuttles, the forward ends of the levers are bifurcated, or, in other words, severally have two portions, $f^2 f^3$, one above the other. Near the rear ends the levers H H' are provided with longitudinal slots s. Passing loosely through the slots s are screws or pins $f^4 f^5$, projecting from the end portions of a bar, f^6 , which is affixed to the upper end of a vertical rock-shaft, f^7 .

When the shaft f^7 is rocked into a position at about right angles to the length of the levers H H', these levers will be forced as far apart as possible at their rear ends, and consequently as close as possible together at their forward ends. The forward ends will then grip shuttles inserted between them. At the lower end the shaft f^7 has affixed to it an arm, f^8 . By shifting this arm f^8 the shaft f^7 will be rocked, so as to operate the levers H H'.

The lever D' is connected to a crank-pin, E', projecting from the disk c^3 of the shaft C', and derives its swinging motion from such crank-pin. It is connected to the said crank-pin by means of a bar, d, loosely mounted on the crank-pin, and having a pivotal connection with links $d' d^2$, which are also pivotally connected with the lever D'. This bar d and the links $d' d^2$ are used in the same way and for the same purpose as the bar and links similarly lettered, which I have heretofore described.

The front end of the lever D' is pivotally connected to one end of a link, d^4 , which, at the other end, is pivotally connected to a car-

riage, F'. When the lever D' is oscillated or swung to and fro, this carriage is reciprocated correspondingly along ways or guides G', which may be similar to the ways or guides 5 for the carriage F.

H² H³ designate levers arranged upon the carriage F'. They are like the levers H H', which are arranged upon the carriage F. They are fulcrumed upon studs f⁹ f¹⁰, projecting from 10 the carriage F', near the forward end of such carriage, or, in other words, near the end which is the nearer to the middle of the loom. The forward ends of the levers H² H³ are adapted to grip the shuttles. In order that 15 two shuttles may be used, the forward ends of these levers are bifurcated, each having two portions, f¹¹ f¹², one above the other. Near the rear ends the levers H² H³ have longitudinal slots s, into which extend screws or pins 20 f¹³ f¹⁴, projecting from a bar, f¹⁵. This bar f¹⁵ is affixed to the upper end of a vertical rock-shaft, f¹⁶, which is journaled in the carriage F', and has affixed to its lower end an arm, f¹⁷. By shifting the arm f¹⁷ the rock-shaft f¹⁶ will 25 be rocked, and the bar f¹⁵ will oscillate the levers H² H³ in such manner that the forward ends of the latter will alternately approach and recede from each other to grip and release the shuttles.

30 The movements of the carriages F F' are so timed that they will approach each other and recede from each other together. The motions of the pair of levers H H', mounted on the carriage F, and of the pair of levers H² H³, mounted on the carriage F', are so 35 timed that when the carriages move into proximity the forward ends of one pair of said levers will move apart and the forward ends of the other pair of said levers will move toward each other, wherefore when the carriages come close together the shuttles will 40 be transferred from one carriage to the other.

In order that the shuttles may always be transferred from one carriage to the other 45 every time the carriages move into proximity with each other, it is necessary that the forward ends of the pair of shuttle-gripping levers of each carriage shall move together on one occasion when the carriages move into 50 proximity, and move apart on the next occasion when the carriages move into proximity, and so on alternately.

I will now describe the means whereby the shafts f⁷ f¹⁶ are rocked for the purpose of operating the shuttle-gripping levers H H' and H² H³.

I I' designate levers which are fulcrumed 60 between the ends to bars G² G³, extending between the ways or guides G G'. These levers work in the same horizontal plane as the arms f⁸ f¹⁷, which are affixed to the shafts f⁷ f¹⁶. When the carriages move into proximity with each other, the arms f⁸ f¹⁷ come in contact with the levers I I', and are shifted so as to 65 rock the shafts f⁷ f¹⁶, because the levers I I' will at those times be adjusted at such angles

that the arms f⁸ f¹⁷, by abutting against them, will be shifted properly.

The levers I I' are connected together by a link, I². The lever I has upon its under side 70 lugs i, in which a rod, I³, fits in such way that while any swinging movement which may be imparted to it will be transmitted to the lever I, yet it will be free to slide lengthwise of the lever I. This rod I³ is pivotally connected to a lever, I⁴, which is pivotally connected by a link, I⁵, with a crank-pin, I⁶, projecting from a gear-wheel, J. The gear-wheel J is mounted on a shaft which is supported by one of the side pieces, A, of the 80 frame. It derives motion from a gear-wheel, J', having one-half the number of teeth which it has, and affixed to the shaft C. Each time the shaft C makes a complete rotation it moves the carriage F as far toward the carriage F' 85 as it can go. The shaft C at the same time moves the carriage F' as far toward the carriage F as it can go. During each rotation of the shaft C the gear-wheel J makes only a half-rotation. Owing to this the wheel J will 90 shift the levers I I' into a different position during each one-half rotation it makes. It is because the levers I I' occupy a different position each time the carriages F F' move into proximity that the forward ends of each 95 of the pairs of shuttle-gripping levers H H' and H² H³ will move toward each other one time when the carriages move into proximity, and move away from each other the next time the carriages move into proximity, and so on.

The shuttles are to have grooves in the sides, into which the portions f² f³ of the levers H H' and f¹¹ f¹² of the levers H² H³ will fit.

What I claim as my invention, and desire to secure by Letters Patent, is—

1. The combination of carriages provided with pairs of shuttle-gripping levers, guides for said carriages, means, substantially such as described, for reciprocating said carriages, oscillating bars connected with the said shuttle-gripping levers, arms connected to the said oscillating bars, so as to move in unison therewith, movable levers for shifting the said arms, and mechanism, substantially such as described, having a connection with one of said levers, which will enable it to be caused to act nearer to or farther from the fulcrum of said lever, substantially as specified.

2. The combination, with carriages provided with pairs of shuttle-gripping levers, of guides for said carriages, means, substantially such as described, for reciprocating the carriages, bars provided with projections engaging with the said shuttle-gripping levers, rock-shafts, to which said bars are affixed, arms affixed to 125 said rock-shafts, movable levers, by contact with which said arms are shifted to operate the said shuttle-gripping levers, and mechanism, substantially such as described, for shifting the said movable levers, substantially as 130 specified.

3. The combination, with reciprocating car-

riages F F', provided with pairs of shuttle-gripper levers H H' and H² H³, of shafts C C' and levers D D', for imparting motion to said carriages, crank-pins E E', carried by the 5 shafts C C', link-connections between the crank-pins E E' and the levers D D', bars f⁶ f¹⁵, provided with pins or screws f⁴ f⁵ f¹³ f¹⁴, entering slots in said shuttle-gripper levers, rock-shafts f⁷ f¹⁶, to which said bars f⁶ f¹⁵ are 10 affixed, arms f⁸ f¹⁷ on said rock-shafts, levers I I', a connection between them, a gear-wheel, J, a connection between the lever I and the gear-wheel J, and a wheel, J', on the shaft C, imparting motion to the gear-wheel J, substantially as specified.
